UNITED STATES PATENT OFFICE.

HOWARD M. BARBER, OF STONINGTON, CONNECTICUT, ASSIGNOR, BY MESNE ASSIGNMENTS, TO C. B. COTTRELL & SONS COMPANY, OF NEW YORK, N. Y., A CORPORATION OF DELAWARE.

SHEET-DELIVERY MECHANISM FOR PRINTING-PRESSES.

1,146,916.

Specification of Letters Patent.

Patented July 20, 1915.

Application filed November 1, 1912. Serial No. 729,003.

To all whom it may concern:

Be it known that I, HOWARD M. BARBER, a citizen of the United States, and resident of Stonington, in the county of New London and State of Connecticut, have invented a new and useful Improvement in Sheet-Delivery Mechanism for Printing-PresSES, of which the following is a specification.

The object of my invention is to provide a novel and efficient means for delivering alternate sheets, cut from a web, in separate piles, and more specifically to means for delivering single sheets, as they are cut from the main web, two at each revolution of the printing press, in two separate piles.

A practical embodiment of my invention is represented in the accompanying drawings, in which—

Figure 1 represents the mechanism partly in end elevation and partly in section, Fig. 2 is a view of the mechanism in side elevation, Fig. 3 is a detail section showing the cam mechanism for controlling the operation of the grippers on the delivery cylinders, and Fig. 4 is a longitudinal vertical section through the mechanism.

The web feeding cylinder is denoted by 1. Means are provided for transversely cutting sheets from the main web, which means is herein shown as a pair of coacting rotary cutters 2, 3.

The two delivery cylinders are denoted by 4, 5, and their grippers by 6, 7, which grippers are arranged to alternately deliver the sheets cut from the main web. Guides 8, 9, are provided for guiding the web from the rotary cutters to the delivery cylinders. The side chains 10 of each of two endless delivery carriers pass around outer pulleys 11 mounted on suitable stud axles 12 and at their inner ends around pulleys 13, mounted on bearings 14 eccentric to the shafts 15 of the delivery cylinders 4 and 5. The side chains 10 pass along guides 16.

Each of these endless delivery carriers is provided with one or more sets of grippers 18 arranged to engage the side edges of the sheet near its advance edge. In the proportion of the parts herein shown, two sets of these grippers are provided on each of the delivery carriers. The eccentric mounting of the inner pulleys 13 permits the inner ends of the side chains to travel within the peripheries of the delivery cylinders 4 and 5

until the bottoms of the delivery cylinders 55 are reached where the sheets are transferred from the delivery cylinder grippers to the endless delivery carrier grippers.

The two sheet receiving tables are denoted by 19 and 20, which tables are arranged beneath the two endless delivery carriers in position to receive the sheets therefrom. These endless delivery carriers are driven at the surface speed of the delivery cylinders and their grippers are so arranged that the sheets are taken alternately and delivered onto the tables 19 and 20.

A retarding mechanism is provided for reducing the speed of the sheets as they are delivered to insure the proper delivery of the sheets onto the tables 19 and 20, which retarding mechanism comprises members carried by the delivery cylinders opposite their grippers, and coacting members carried by the frame. Each of the cylinder members comprises a series of spring pressed arms 21, the free ends of which arms are preferably provided with rollers 22, and each of the coacting members comprises a series of spring pressed shoes 23 carried by a rocking lever 24. These two rocking levers 24 are connected to move together by a rod 25 and a common rock lever 26 having a crank and pitman connection 27, 28, with the shaft of 80 one of the delivery cylinders, in the present instance the delivery cylinder 4. Fixed cams 29, 30, have, respectively, cam surfaces 31, 32, for engaging their respective arms to open the grippers 6, 7, to receive the advance edge of the web. These cams 29 and 30 are also provided, respectively, with cam surfaces 33, 34, for opening the grippers to transfer the control of the sheets from said grippers to the corresponding grippers on the endless delivery carriers at the proper times.

Fixed cams 35, are arranged in pairs at the inner end of each endless delivery carrier and are provided with cam surfaces 36 arranged to engage the arms of the endless delivery carrier grippers for opening the grippers at the proper time to receive the advance side edges of the sheets and close upon the same to take the control of said sheets from the delivery cylinder grippers.

A pair of fixed cams 37 is arranged at the outer end of each of the endless delivery car-

riers and the said cams are provided with surfaces 38 arranged to engage the arms of the endless delivery carrier grippers at the proper time for releasing the sheets to deliver them onto the sheet receiving table 19 or 20.

A fixed cam 39 is provided for each set of rocking arms 21, said cams being arranged to rock the said arms outwardly into co-action with the shoes 23 for clamping the rear portion of the sheets being delivered between them, a sufficient time to reduce the speed of the sheet before it drops onto its receiving table.

15 The movement of the shoes 23 is slower than the movement of the delivery cylinder and endless delivery carriers. As the rocking arms are carried by the delivery cylinders, their rollers 22 will roll along the 20 sheet held between them and the shoes 23 while still clamping the sheet to the shoes 23 for reducing the speed of the sheets. The delivery cylinders are driven at the speed of the press through the gears 40, 41, 42, 43, 25 so that each cylinder delivers a single sheet at each revolution of the press. The rotary cutters 2 and 3 are driven at the proper speed through the gears 42, 45, 46, to cut two sheets from the web for every revolution 30 of the press. The feed cylinder 1 is driven at the proper speed through the gears 48, 49, 50, 51. The endless delivery carriers are driven at the surface speed of the delivery cylinders through gears 52, 53, on the shafts 35 54, 55, of the gears 44, 45, which gears 52, 53, mesh with the teeth on the side chains of the said delivery carriers.

The operation of the delivery mechanism is as follows:—The web passes around the 40 feed cylinder 1 and downwardly through the cutters 2, 3, guides 8, 9, to the delivery cylinders 4, 5. The grippers on one of these cylinders engage the advance edge of the web at the point *x* and as the grippers 45 reach the point *y* at the under side of the endless delivery carrier the web is severed transversely by the cutters 2 and 3 to form a sheet and the control of the sheet is transferred from the grippers on the delivery 50 cylinder to the grippers on the endless delivery carrier at the point where the paths of the two sets of grippers coincide and the said endless delivery carrier grippers will then lead the sheet outwardly along the under side of the delivery carrier at the surface 55 speed of the delivery cylinders. As the sheet reaches a position nearly over its receiving table, the retarding mechanism for that particular delivery is brought into action as the 60 advance side edges of the sheet are released from the endless delivery carrier grippers and the speed of the sheet is thereby reduced as it drops onto its sheet receiving table. In the meantime, the advance edge of the web 65 is fed downwardly through the guides 8 and

9 and is engaged at the point *x* by the grippers on the other delivery cylinder and the same operation is carried out by its delivery carrier and retarding device.

By causing the grippers on each delivery 70 cylinder and its endless carrier to travel in circular paths eccentric to each other at the inner end of the endless carrier, the grippers on the endless carrier may be caused to travel at the same surface speed as the 75 grippers on the delivery cylinder and be brought into coaction with said grippers at one point, *i. e.*, the transfer point, and at all other times be out of the path of said delivery cylinder grippers, and by causing the 80 grippers on the endless delivery carrier to engage the side edges of the sheets, no cross bars connecting the side chains of the endless delivery carrier are needed and the grippers on the endless delivery carrier do not travel 85 around the periphery of the delivery cylinder, but leave it free for the unobstructed passage of the web sheets.

By the term "delivery cylinder" I wish to include any rotary support for the grippers which travel in a circular path for transferring the sheets cut from the main web, to the endless delivery carrier grippers.

It is evident that slight changes might be resorted to in the form, construction and arrangement of the several parts without departing from the spirit and scope of my invention; hence I do not wish to limit myself strictly to the structure herein set forth, but

What I claim is:—

1. A flat sheet delivery mechanism including means for cutting sheets from the running web, a delivery cylinder, an endless delivery carrier, grippers on the cylinder and carrier arranged to coact to transfer the sheets from the cylinder to the carrier, and means for reducing the speed of the sheets after they are released from the carrier grippers.

2. A flat sheet delivery mechanism including means for cutting sheets from the running web, a delivery cylinder driven at a certain surface speed, an endless delivery carrier driven at the same surface speed around the axis of the delivery cylinder and grippers on the cylinder and carrier arranged to coact to transfer the sheets from the cylinder to the carrier.

3. A flat sheet delivery mechanism including means for cutting sheets from the running web, a delivery cylinder driven at a certain surface speed, an endless delivery carrier driven at the same surface speed around the axis of the delivery cylinder, grippers on the cylinder and carrier arranged to coact to transfer the sheets from the cylinder to the carrier, and means for reducing the speed of the sheets as they are released from the carrier grippers.

4. A flat sheet delivery mechanism including means for cutting sheets from the running web, a delivery cylinder, an endless delivery carrier, grippers on the cylinder arranged to engage the advance edge of the sheets and grippers on the carrier arranged to engage the side edges of the sheet, said grippers being arranged to coact to transfer the sheets from the cylinder to the carrier.
5. A flat sheet delivery mechanism including means for cutting sheets from the running web, a delivery cylinder, an endless delivery carrier, grippers on the cylinder arranged to engage the advance edge of the sheets, grippers on the carrier arranged to engage the side edges of the sheet, said grippers being arranged to coact to transfer the sheets from the cylinder to the carrier, and means for reducing the speed of the sheets as they are released from the carrier grippers.
6. A flat sheet delivery mechanism including means for cutting sheets from the running web, a delivery cylinder driven at a certain surface speed, an endless delivery carrier driven at the same surface speed around the axis of the delivery cylinder, grippers on the cylinder arranged to engage the advance edges of the sheets and grippers on the carrier arranged to engage the side edges of the sheets, said grippers being arranged to coact to transfer the sheets from the cylinder to the carrier.
7. A flat sheet delivery mechanism including means for cutting sheets from the running web, a delivery cylinder driven at a certain surface speed, an endless delivery carrier driven at the same surface speed as the delivery cylinder, grippers on the cylinder arranged to engage the advance edges of the sheets and grippers on the carrier arranged to engage the side edges of the sheets, said grippers being arranged to coact to transfer the sheets from the cylinder to the carrier and means for reducing the speed of the sheets as they are released from the carrier grippers.
8. A flat sheet delivery mechanism including means for cutting sheets from the running web, a delivery cylinder, an endless delivery carrier and grippers on the cylinder and carrier arranged to coact at a certain point to transfer the sheets from the cylinder to the carrier, the axis of the cylinder being located within the path of the carrier, and means for reducing the speed of the sheets after they are released from the carrier grippers.
9. A flat sheet delivery mechanism including means for cutting sheets from the running web, a delivery cylinder driven at a certain surface speed, an endless delivery carrier driven at the same surface speed and grippers on the cylinder and carrier arranged to coact at a certain point to transfer the sheets from the cylinder to the car-
- rier, the axis of the cylinder being located within the path of the carrier.
10. A flat sheet delivery mechanism including means for cutting sheets from the running web, a delivery cylinder driven at a certain speed, an endless delivery carrier driven at the same surface speed, grippers on the cylinder and carrier arranged to coact at a certain point to transfer the sheets from the cylinder to the carrier, the axis of the cylinder being located within the path of the carrier, and means for reducing the speed of the sheets as they are released from the carrier grippers.
11. A flat sheet delivery mechanism including means for cutting sheets from the running web, a delivery cylinder, an endless delivery carrier, grippers on the cylinder arranged to engage the advance edges of the sheets and grippers on the carrier arranged to engage the side edges of the sheets, said grippers being arranged to coact at a certain point to transfer the sheets from the cylinder to the carrier, the axis of the cylinder being located within the path of the carrier.
12. A flat sheet delivery mechanism including means for cutting sheets from the running web, a delivery cylinder, an endless delivery carrier, grippers on the cylinder arranged to engage the advance edges of the sheets, grippers on the carrier arranged to engage the side edges of the sheets, said grippers being arranged to coact at a certain point to transfer the sheets from the cylinder to the carrier, the axis of the cylinder being located within the path of the carrier, and means for reducing the speed of the sheets as they are released from the carrier grippers.
13. A flat sheet delivery mechanism including means for cutting sheets from the running web, a delivery cylinder driven at a certain surface speed, an endless delivery carrier driven at the same surface speed as the delivery cylinder, grippers on the cylinder arranged to engage the advance edges of the sheets and grippers on the carrier arranged to engage the side edges of the sheets, said grippers being arranged to coact at a certain point to transfer the sheets from the cylinder to the carrier, the axis of the cylinder being located within the path of the carrier.
14. A flat sheet delivery mechanism including means for cutting sheets from the running web, a delivery cylinder driven at a certain surface speed, an endless delivery carrier driven at the same surface speed as the delivery cylinder, grippers on the cylinder arranged to engage the advance edges of the sheets, grippers on the carrier arranged to engage the side edges of the sheets, said grippers being arranged to coact at a certain point to transfer the sheets from the cylinder to the carrier.

der to the carrier, the axis of the cylinder being located within the path of the carrier, and means for reducing the speed of the sheets as they are released from the carrier 5 grippers.

15. A flat sheet delivery mechanism including means for cutting sheets from the running web, a delivery cylinder, an endless delivery carrier arranged to travel in a 10 partly circular and partly non-circular path, the axis of the cylinder being located within and eccentric to the circular portion of the path of the carrier, and grippers on the cylinder and carrier arranged to coact at a certain 15 point to transfer the sheets from the cylinder to the carrier.

16. A flat sheet delivery mechanism including means for cutting sheets from the running web, a delivery cylinder, an endless 20 delivery carrier arranged to travel in a partly circular and partly non-circular path, the axis of the cylinder being located within and eccentric to the circular portion of the path of the carrier, grippers on the cylinder 25 and carrier arranged to coact at a certain point to transfer the sheets from the cylinder to the carrier, and means for reducing the speed of the sheets after they are released from the carrier grippers.

30 17. A flat sheet delivery mechanism including means for cutting sheets from the running web, a delivery cylinder driven at a certain surface speed, an endless delivery carrier driven at the same surface speed, the 35 axis of the cylinder being located within and eccentric to the path of the carrier at its inner end and grippers on the cylinder and carrier arranged to coact at a certain point to transfer the sheets from the cylinder to 40 the carrier.

18. A flat sheet delivery mechanism including means for cutting sheets from the running web, a delivery cylinder driven at a certain surface speed, an endless delivery 45 carrier driven at the same surface speed, the axis of the cylinder being located within and eccentric to the path of the carrier at its inner end, grippers on the cylinder and carrier arranged to coact at a certain point to 50 transfer the sheets from the cylinder to the carrier, and means for reducing the speed of the sheets as they are released from the carrier grippers.

55 19. A flat sheet delivery mechanism including means for cutting sheets from the running web, a delivery cylinder, an endless delivery carrier arranged to travel in a partly circular and partly non-circular path, the axis of the cylinder being located 60 within and eccentric to the circular portion of the path of the carrier, grippers on the cylinder arranged to engage the advance edges of the sheets and grippers on the carrier arranged to engage the side edges of 65 the sheets, said grippers being arranged to

coact at a certain point to transfer the sheets from the cylinder to the carrier.

20. A flat sheet delivery mechanism including means for cutting sheets from the running web, a delivery cylinder arranged 70 to travel in a partly circular and partly non-circular path, an endless delivery carrier, the axis of the cylinder being located within and eccentric to the circular portion of the path of the carrier, grippers on the cylinder arranged to engage the advance edges of the sheets and grippers on the carrier arranged to engage the side edges of the sheets, said grippers being arranged to coact at a certain point to transfer the sheets 75 from the cylinder to the carrier, and means for reducing the speed of the sheets as they are released from the carrier grippers.

80 21. A flat sheet delivery mechanism including means for cutting sheets from the running web, a delivery cylinder driven at a certain surface speed, an endless delivery carrier driven at the same surface speed, the axis of the cylinder being located within and eccentric to the path of the carrier 85 at its inner end, grippers on the cylinder arranged to engage the advance edges of the sheets and grippers on the carrier arranged to engage the side edges of the sheets, the said grippers being arranged to coact at a 90 certain point to transfer the sheets from the cylinder to the carrier.

95 22. A flat sheet delivery mechanism including means for cutting sheets from the running web, a delivery cylinder driven at a certain surface speed, an endless delivery carrier driven at the same surface speed, the axis of the cylinder being located within and eccentric to the path of the carrier 100 at its inner end, grippers on the cylinder 105 arranged to engage the advance edges of the sheets, grippers on the carrier arranged to engage the side edges of the sheets, the said grippers being arranged to coact at a certain point to transfer the sheets from the cylinder to the carrier, and means for reducing the speed of the sheets as they are 110 released from the carrier grippers.

115 23. A flat sheet delivery mechanism including a set of grippers arranged to travel in a circular path, another set of grippers arranged to travel in a partly circular and partly non-circular path, the paths of the two sets of grippers coinciding at a certain point, means operating said grippers to 120 transfer the control of the sheets from one to the other at said point, and means for reducing the speed of the sheets after they are released from the last-named grippers.

125 24. A flat sheet delivery mechanism including a set of grippers arranged to travel in a circular path at a certain surface speed, another set of grippers arranged to travel at the same surface speed as the first-named set of grippers in a partly circular and 130

- partly non-circular path around the axis of the path of the first-named set of grippers, the paths of the two sets of grippers coinciding at a certain point, means operating said grippers to transfer the control of the sheets from one to the other at said point, and means for reducing the speed of the sheets as they are released from the last-named grippers. 5
25. A flat sheet delivery mechanism including a set of grippers arranged to travel in a circular path and arranged to engage the advance edges of the sheets, another set of grippers arranged to travel in a partly circular and partly non-circular path around the axis of the path of the first-named set of grippers and arranged to engage the side edges of the sheets, the paths of the two sets of grippers coinciding at a certain point and means operating said grippers to transfer the control of the sheets from one to the other at said point. 10
26. A flat sheet delivery mechanism including a set of grippers arranged to travel in a circular path and arranged to engage the advance edges of the sheets, another set of grippers arranged to travel in a partly circular and partly non-circular path around the axis of the path of the first-named set of grippers and arranged to engage the side edges of the sheets, the paths of the two sets of grippers coinciding at a certain point, means operating said grippers to transfer the control of the sheets from one to the other at said point, and means for reducing the speed of the sheets as they are released from the last-named grippers. 15
27. A flat sheet delivery mechanism including a set of grippers arranged to travel at a certain surface speed in a circular path, another set of grippers arranged to travel at the same surface speed as the first-named set of grippers in a partly circular and partly non-circular path around the axis of the path of the first-named set of grippers, the first named set of grippers being arranged to engage the advance edges of the sheets and the last-named set of grippers being arranged to engage the side edges of the sheets, the paths of the two sets of grippers coinciding at a certain point and means operating said grippers to transfer the control of the sheets from one to the other at said point. 20
28. A flat sheet delivery mechanism including a set of grippers arranged to travel at a certain surface speed in a circular path, another set of grippers arranged to travel at the same surface speed as the first-named set of grippers in a partly circular and partly non-circular path around the axis of the path of the first-named set of grippers, the first set of grippers being arranged to engage the advance edges of the sheets and the last-named set of grippers being arranged to engage the side edges of the sheets, the paths of the two sets of grippers coinciding at a certain point and means operating said grippers to transfer the control of the sheets from one to the other at said point, and means for reducing the speed of the sheets as they are released from the last-named grippers. 25
29. A flat sheet delivery mechanism including a set of grippers arranged to travel in a circular path, another set of grippers arranged to travel in a circular path eccentric to the path of the first-named set of grippers and also in a non-circular path, the paths of the two sets of grippers coinciding at a certain point and means operating said grippers to transfer the control of the sheets from one to the other at said point. 30
30. A flat sheet delivery mechanism including a set of grippers arranged to travel in a circular path, another set of grippers arranged to travel in a circular path eccentric to the path of the first-named set of grippers and also in a non-circular path, the paths of the two sets of grippers coinciding at a certain point, means operating said grippers to transfer the control of the sheets from one to the other at said point, and means for reducing the speed of the sheets as they are released from the last-named grippers. 35
31. A flat sheet delivery mechanism including a set of grippers arranged to travel at a certain surface speed in a circular path, another set of grippers arranged to travel at the same surface speed in a circular path around the axis of the path of the first-named set of grippers and eccentric thereto and also in a non-circular path, the paths of the two sets of grippers coinciding at a certain point and means operating said grippers to transfer the control of the sheets from one to the other at said point. 40
32. A flat sheet delivery mechanism including a set of grippers arranged to travel at a certain surface speed in a circular path, another set of grippers arranged to travel at the same surface speed in a circular path around the axis of the path of the first-named set of grippers and eccentric thereto and also in a non-circular path, the paths of the two sets of grippers coinciding at a certain point, means operating said grippers to transfer the control of the sheets from one to the other at said point, and means for reducing the speed of the sheets as they are released from the last-named grippers. 45
33. A flat sheet delivery mechanism including a set of grippers arranged to travel in a circular path, another set of grippers arranged to travel in a circular path around the axis of the path of the first-named set of grippers and eccentric thereto and in a non-circular path, the first named set of 50

grippers being arranged to engage the advance edges of the sheets and the last named set of grippers being arranged to engage the side edges of the sheets, the paths of the two sets of grippers coinciding at a certain point and means operating said grippers to transfer the control of the sheets from one to the other at said point.

34. A flat sheet delivery mechanism including a set of grippers arranged to travel in a circular path, another set of grippers arranged to travel in a circular path around the axis of the path of the first-named set of grippers and eccentric thereto and in a non-circular path, the first-named set of grippers being arranged to engage the advance edges of the sheets and the last named set of grippers being arranged to engage the side edges of the sheets, the paths of the two sets of grippers coinciding at a certain point, means operating said grippers to transfer the control of the sheets from one to the other at said point, and means for reducing the speed of the sheets as they are released from the last-named grippers.

35. A flat sheet delivery mechanism including a set of grippers arranged to travel at a certain surface speed in a circular path, another set of grippers arranged to travel at the same surface speed in a circular path around the axis of the path of the first-named set of grippers and eccentric thereto and also in a non-circular path, the first-named grippers being arranged to engage the advance edges of the sheets and the last-named grippers being arranged to engage the side edges of the sheets, the paths of the two sets of grippers coinciding at a certain point and means operating said grippers to transfer the control of the sheets from one to the other at said point.

36. A flat sheet delivery mechanism including a set of grippers arranged to travel at a certain surface speed in a circular path, another set of grippers arranged to travel at the same surface speed as the first-named set of grippers in a circular path around the axis of the path of the first-named set of grippers and eccentric thereto and also in a non-circular path, the first-named grippers being arranged to engage the advance edges of the sheets and the last-named grippers being arranged to engage the side edges of the sheets, the paths of the two sets of grippers coinciding at a certain point, means operating said grippers to transfer the control of the sheets from one to the other at said point, and means for reducing the speed of the sheets as they are released from the last-named grippers.

37. A double flat sheet delivery mechanism including means for cutting sheets from the running web, two delivery cylinders, two endless delivery carriers, grippers on the cylinders and carriers arranged to

coact to transfer alternate sheets from the cylinders to their respective carriers, and means for reducing the speed of the sheets after they are released from their respective carriers.

38. A double flat sheet delivery mechanism including means for cutting sheets from the running web, two delivery cylinders driven at a certain surface speed, two endless delivery carriers driven at the same surface speed as the delivery cylinders and grippers on the cylinders and carriers arranged to coact to transfer alternate sheets from the cylinders to their respective carriers.

39. A double flat sheet delivery mechanism including means for cutting sheets from the running web, two delivery cylinders driven at a certain surface speed, two endless delivery carriers driven at the same surface speed as the delivery cylinders, grippers on the cylinders and carriers arranged to coact to transfer alternate sheets from the cylinders to their respective carriers, and means for reducing the speed of the sheets as they are released from their respective carriers.

40. A double flat sheet delivery mechanism including means for cutting sheets from the running web, two delivery cylinders, two endless delivery carriers, grippers on the cylinders arranged to engage the advance edges of alternate sheets and grippers on the carriers arranged to engage the side edges of alternate sheets, said grippers being arranged to coact to transfer alternate sheets from the cylinders to their respective carriers.

41. A double flat sheet delivery mechanism including means for cutting sheets from the running web, two delivery cylinders, two endless delivery carriers, grippers on the cylinders arranged to engage the advance edges of alternate sheets, grippers on the carriers arranged to engage the side edges of alternate sheets, said grippers being arranged to coact to transfer alternate sheets from the cylinders to their respective carriers, and means for reducing the speed of the sheets as they are released from their respective carriers.

42. A double flat sheet delivery mechanism including means for cutting sheets from the running web, two delivery cylinders driven at a certain surface speed, two endless delivery carriers driven at the same surface speed as the delivery cylinders, grippers on the cylinders arranged to engage the advance edges of alternate sheets and grippers on the carriers arranged to engage the side edges of alternate sheets, said grippers being arranged to coact to transfer alternate sheets from the cylinders to their respective carriers.

43. A double flat sheet delivery mecha-

nism including means for cutting sheets from the running web, two delivery cylinders driven at a certain surface speed, two endless delivery carriers driven at the same 5 surface speed as the delivery cylinders, grippers on the cylinders arranged to engage the advance edges of alternate sheets, grippers on the carriers arranged to engage the side edges of alternate sheets, said grippers being arranged to coact to transfer alternate sheets from the cylinders to their respective carriers, and means for reducing the speed of the sheets as they are released from their respective carriers.

10 44. A double flat sheet delivery mechanism including means for cutting sheets from the running web, two delivery cylinders driven at a certain surface speed, two endless delivery carriers driven at the same 15 surface speed as the delivery cylinders and grippers on the cylinders and carriers arranged to coact at certain points to transfer alternate sheets from the cylinders to their respective carriers, the axes of the cylinders 20 being located within the paths of their respective carriers.

25 45. A double flat sheet delivery mechanism including means for cutting sheets from the running web, two delivery cylinders driven at a certain surface speed, two endless delivery carriers driven at the same surface speed as the delivery cylinders, grippers on the cylinders and carriers arranged to coact at certain points to transfer 30 alternate sheets from the cylinders to their respective carriers, the axes of the cylinders being located within the paths of their respective carriers, and means for reducing the speed of the sheets as they are released 35 from their respective carriers.

40 46. A double flat sheet delivery mechanism including means for cutting sheets from the running web, two delivery cylinders, two endless delivery carriers, grippers on the cylinders arranged to engage the advance edges of alternate sheets and grippers on the carriers arranged to engage the side edges of alternate sheets, said grippers being arranged to coact at certain points to 45 transfer alternate sheets from the cylinders to their respective carriers, the axes of the cylinders being located within the path of the carriers.

50 47. A double flat sheet delivery mechanism including means for cutting sheets from the running web, two delivery cylinders, two endless delivery carriers, grippers on the cylinders arranged to engage the advance edges of alternate sheets, grippers on the 55 carriers arranged to engage the side edges of alternate sheets, said grippers being arranged to coact at certain points to transfer alternate sheets from the cylinders to their respective carriers, the axes of the cylinders being located within the path of the carriers.

carriers, and means for reducing the speed of the sheets as they are released from their respective carriers.

48. A double flat sheet delivery mechanism including means for cutting sheets from the running web, two delivery cylinders driven at a certain surface speed, two endless delivery carriers driven at the same surface speed as the delivery cylinders, grippers on the cylinders arranged to engage the advance edges of alternate sheets and grippers on the carriers arranged to engage the side edges of alternate sheets, said grippers being arranged to coact at certain points to transfer alternate sheets from the cylinders to their respective carriers, the axes of the cylinders being located within the paths of their respective carriers.

55 49. A double flat sheet delivery mechanism including means for cutting sheets from the running web, two delivery cylinders driven at a certain surface speed, two endless delivery carriers driven at the same surface speed as the delivery cylinders, grippers on the cylinders arranged to engage the advance edges of alternate sheets, grippers on the carriers arranged to engage the side edges of alternate sheets, said grippers being arranged to coact at certain points to transfer alternate sheets from the cylinders to their respective carriers, the axes of the cylinders being located within the paths of their respective carriers, and means for reducing the speed of the sheets as they are released from their respective carriers.

60 50. A double flat sheet delivery mechanism including means for cutting sheets from the running web, two delivery cylinders, two endless delivery carriers traveling in circular paths at their inner ends, the axes of the cylinders being located within and eccentric to the paths of the carriers at their inner ends and grippers on the cylinders and carriers arranged to coact at certain points to transfer the sheets from the cylinders to their respective carriers.

51. A double flat sheet delivery mechanism including means for cutting sheets from the running web, two delivery cylinders, two endless delivery carriers traveling in circular paths at their inner ends, the axes of the cylinders being located within and eccentric to the paths of the carriers at their inner ends, grippers on the cylinders and carriers arranged to coact at certain points to transfer the sheets from the cylinders to their respective carriers, and means for reducing the speed of the sheets after they are released from their respective carriers.

55 52. A double flat sheet delivery mechanism including means for cutting sheets from the running web, two delivery cylinders driven at a certain surface speed, two endless delivery carriers driven at the same surface speed as the delivery cylinders, the axes of the cylinders being located within the paths of the carriers.

the cylinders being located within and eccentric to the paths of the carriers at their inner ends and grippers on the cylinders and carriers arranged to coact at certain points to 65
5 transfer the sheets from the cylinders to their respective carriers.

53. A double flat sheet delivery mechanism including means for cutting sheets from the running web, two delivery cylinders driven 10 at a certain surface speed, two endless delivery carriers driven at the same surface speed as the delivery cylinders, the axes of the cylinders being located within and eccentric to the paths of the carriers at their inner ends, grippers on the cylinders and carriers arranged to coact at certain points to 15 transfer the sheets from the cylinders to their respective carriers, and means for reducing the speed of the sheets as they are 20 released from their respective carriers.

54. A double flat sheet delivery mechanism including means for cutting sheets from the running web, two delivery cylinders, two endless delivery carriers traveling in circular paths at their inner ends, the axes of the cylinders being located within and eccentric to the paths of the carriers at their inner ends, grippers on the cylinders arranged to engage the advance edges of alternate sheets 25 and grippers on the carriers arranged to engage the side edges of alternate sheets, said grippers being arranged to coact at certain points to transfer alternate sheets from the cylinders to their respective carriers. 30

55. A double flat sheet delivery mechanism including means for cutting sheets from the running web, two delivery cylinders, two endless delivery carriers traveling 40 in circular paths at their inner ends, the axes of the cylinders being located within and eccentric to the paths of the carriers and at their inner ends, grippers on the cylinders arranged to engage the advance edges 45 of alternate sheets, grippers on the carriers arranged to engage the side edges of alternate sheets, said grippers being arranged to coact at certain points to transfer alternate sheets from the cylinders to their respective carriers, and means for reducing 50 the speed of the sheets as they are released from their respective carriers.

56. A double flat sheet delivery mechanism including means for cutting sheets 55 from the running web, two delivery cylinders driven at a certain surface speed, two endless delivery carriers driven at the same surface speed as the delivery cylinders, the axes of the cylinders being located within 60 and eccentric to the paths of the carriers at their inner ends, grippers on the cylinders arranged to engage the advance edges of alternate sheets and grippers on the carriers arranged to engage the side edges of alter-

nate sheets, the said grippers being arranged to coact at certain points to transfer alternate sheets from the cylinders to their respective carriers. 65

57. A double flat sheet delivery mechanism including means for cutting sheets 70 from the running web, two delivery cylinders driven at a certain surface speed, two endless delivery carriers driven at the same surface speed as the delivery cylinders, the axes of the cylinders being located within 75 and eccentric to the circular paths of the carriers at their inner ends, grippers on the cylinders arranged to engage the advance edges of alternate sheets, grippers on the carriers arranged to engage the side edges of 80 alternate sheets, the said grippers being arranged to coact at certain points to transfer alternate sheets from the cylinders to their respective carriers, and means for reducing the speed of the sheets as they are 85 released from their respective carriers.

58. A double flat sheet delivery mechanism including two sets of grippers arranged to travel in circular paths at a certain surface speed, two more sets of grippers 90 arranged to travel at the same surface speed as the first-named sets of grippers in partly circular and partly non-circular paths, the paths of the first named sets of grippers coinciding at certain points with the paths of 95 the last-named sets of grippers and means operating the grippers to transfer the control of alternate sheets from the first-named sets of grippers to the last-named sets of grippers. 100

59. A double flat sheet delivery mechanism including two sets of grippers arranged to travel in circular paths at a certain surface speed, two more sets of grippers arranged to travel at the same surface speed as the first-named sets of grippers in partly circular and partly non-circular paths, the paths of the first-named sets of grippers coinciding at certain points with the paths of the last-named sets of grippers, 105 means operating the grippers to transfer the control of alternate sheets from the first-named sets of grippers to the last-named sets of grippers, 110 and means for reducing the speed of the sheets as they are released from 115 the last-named sets of grippers.

60. A double flat sheet delivery mechanism including two sets of grippers arranged to travel in circular paths and arranged to engage the advance edges of alternate sheets, two more sets of grippers arranged to travel in partly circular and partly non-circular paths and arranged to engage the side edges of alternate sheets, the paths of the first-named sets of grippers coinciding at certain points with the paths of the last-named sets of grippers and means 120 operating the grippers to transfer the con- 125

trof of alternate sheets from the first-named sets of grippers to the last-named sets of grippers.

61. A double flat sheet delivery mechanism including two sets of grippers arranged to travel in circular paths and arranged to engage the advance edges of alternate sheets, two more sets of grippers arranged to travel in partly circular and partly non-circular paths and arranged to engage the side edges of alternate sheets, the paths of the first-named sets of grippers coinciding at certain points with the paths of the last-named sets of grippers, means operating the grippers to transfer the control of alternate sheets from the first-named sets of grippers to the last-named sets of grippers, and means for reducing the speed of the sheets as they are released from the last-named sets of grippers.

62. A double flat sheet delivery mechanism including two sets of grippers arranged to travel at a certain surface speed in circular paths, two more sets of grippers arranged to travel at the same surface speed as the first-named sets of grippers in partly circular and partly non-circular paths, the first-named sets of grippers being arranged to engage the advance edges of alternate sheets and the last-named sets of grippers being arranged to engage the side edges of alternate sheets, the paths of the first-named sets of grippers coinciding at certain points with the paths of the last-named sets of grippers and means operating the grippers to transfer the control of alternate sheets from the first-named sets of grippers to the last-named sets of grippers.

63. A double flat sheet delivery mechanism including two sets of grippers arranged to travel at a certain surface speed in circular paths, two more sets of grippers arranged to travel at the same surface speed as the first-named sets of grippers in partly circular and partly non-circular paths, the first-named sets of grippers being arranged to engage the advance edges of alternate sheets and the last-named sets of grippers being arranged to engage the side edges of alternate sheets, the paths of the first-named sets of grippers coinciding with the paths of the last-named sets of grippers, means operating the grippers to transfer the control of alternate sheets from the first-named sets of grippers to the last-named sets of grippers, and means for reducing the speed of the sheets as they are released from the last-named sets of grippers.

64. A double flat sheet delivery mechanism including two sets of grippers arranged to travel in circular paths, two more sets of grippers arranged to travel in circular paths eccentric to the circular paths of the first-named sets of grippers and also

in non-circular paths, the paths of the first-named sets of grippers coinciding at certain points with the paths of the last-named sets of grippers and means operating the grippers to transfer the control of alternate sheets from the first-named sets of grippers to the last-named sets of grippers.

65. A double flat sheet delivery mechanism including two sets of grippers arranged to travel in circular paths, two more sets of grippers arranged to travel in circular paths eccentric to the circular paths of the first-named sets of grippers and also in non-circular paths, the paths of the first-named sets of grippers coinciding at certain points with the paths of the last-named sets of grippers, means operating the grippers to transfer the control of alternate sheets from the first-named sets of grippers to the last-named sets of grippers, and means for reducing the speed of the sheets after they are released from the last-named sets of grippers.

66. A double flat sheet delivery mechanism including two sets of grippers arranged to travel at a certain surface speed in circular paths, two more sets of grippers arranged to travel at the same surface speed as the first-named sets of grippers in circular paths eccentric to the paths of the first-named sets of grippers and also in non-circular paths, the paths of the first-named sets of grippers coinciding at certain points with the paths of the last-named sets of grippers and means operating the grippers to transfer the control of alternate sheets from the first-named sets of grippers to the last-named sets of grippers.

67. A double flat sheet delivery mechanism including two sets of grippers arranged to travel at a certain surface speed in circular paths, two more sets of grippers arranged to travel at the same surface speed as the first-named sets of grippers, in circular paths eccentric to the paths of the first-named sets of grippers, and also in a non-circular path, the paths of the first-named sets of grippers coinciding at certain points with the paths of the last-named sets of grippers, means operating the grippers to transfer the control of alternate sheets from the first-named sets of grippers to the last-named sets of grippers, and means for reducing the speed of the sheets as they are released from the last-named sets of grippers.

68. A double flat sheet delivery mechanism including two sets of grippers arranged to travel in circular paths, two more sets of grippers arranged to travel in circular paths eccentric to the circular paths of the first-named sets of grippers, and in non-circular paths, the first-named sets of grippers being arranged to engage the advance edges of alternate sheets and the last-named sets

of grippers being arranged to engage the side edges of alternate sheets, the paths of the first-named sets of grippers coinciding at certain points with the paths of the last-named sets of grippers and means operating said grippers to transfer the control of alternate sheets from the first-named sets of grippers to the last-named sets of grippers.

69. A double flat sheet delivery mechanism including two sets of grippers arranged to travel in circular paths, two more sets of grippers arranged to travel in circular paths eccentric to the circular paths of the first-named sets of grippers and in non-circular paths, the first-named sets of grippers being arranged to engage the advance edges of alternate sheets and the last-named sets of grippers being arranged to engage the side edges of alternate sheets, the paths of the first-named sets of grippers coinciding at certain points with the paths of the last-named sets of grippers, means operating said grippers to transfer the control of alternate sheets from the first-named sets of grippers to the last-named sets of grippers, and means for reducing the speed of the sheets as they are released from the last-named sets of grippers.

70. A double flat sheet delivery mechanism including two sets of grippers arranged to travel at a certain surface speed in circular paths, two more sets of grippers arranged to travel at the same surface speed as the first-named sets of grippers in circular paths eccentric thereto and also in non-circular paths, the first-named sets of grippers being arranged to engage the advance edges of alternate sheets and the last-named sets of grippers being arranged to engage the side edges of alternate sheets, the paths of the first-named sets of grippers coinciding at certain points with the paths of the last-named sets of grippers and means operating the grippers to transfer the control of alternate sheets from the first-named sets of grippers to the last-named sets of grippers.

71. A double flat sheet delivery mechanism including two sets of grippers arranged to travel at a certain surface speed in circular paths, two more sets of grippers

arranged to travel at the same surface speed as the first-named sets of grippers in circular paths eccentric thereto and also in non-circular paths, the first-named sets of grippers being arranged to engage the advance edges of alternate sheets and the last-named sets of grippers being arranged to engage the side edges of alternate sheets, the paths of the first-named sets of grippers coinciding at certain points with the paths of the last-named sets of grippers, means operating the grippers to transfer the control of alternate sheets from the first-named sets of grippers to the last-named sets of grippers, and means for reducing the speed of the sheets as they are released from the last-named sets of grippers.

72. A double flat sheet delivery mechanism including two tables, two endless delivery carriers arranged to convey alternate sheets outwardly and deliver them onto said tables and retarding devices arranged to engage said sheets for reducing their speed as they are being delivered.

73. A flat sheet delivery mechanism including a table, a delivery cylinder, an endless carrier arranged to take a sheet therefrom, convey it outwardly and deliver it onto said table and a retarding device comprising a member carried by the delivery cylinder and a member coacting therewith for engaging the sheet to reduce its speed as it is being delivered.

74. A double flat sheet delivery mechanism including two tables, two delivery cylinders, two endless carriers arranged to take alternate sheets from said cylinders, convey them outwardly and deliver them onto said tables and retarding devices comprising members carried by the delivery cylinders and members coacting therewith for engaging the sheets to reduce their speed as they are being delivered.

In testimony, that I claim the foregoing as my invention, I have signed my name in presence of two witnesses, this thirty-first day of October, 1912.

HOWARD M. BARBER.

Witnesses:

F. GEORGE BARRY,
C. S. SUNDGREN.
